[57] CLAIM

The ornamental design for a recycling container for aluminum cans, as shown and described.

DESCRIPTION

FIG. 1 is a front elevational view of a recycling container for aluminum cans showing my new design;

FIG. 2 is a rear elevational view thereof;

FIG. 3 is a side elevational view thereof;

FIG. 4 is a side elevational view thereof, said side being opposite to that side shown in FIG. 3;

FIG. 5 is a top elevational view thereof; and,

FIG. 6 is a bottom elevational view thereof.

FIG. 1

FIG. 2

FIG. 3

FIG. 4

FIG. 5

FIG. 6
